UNITED STATES PATENT OFFICE.

JOHANNES CHRISTIAN JOHANSEN, OF LONDON, ENGLAND.

MASSAGE APPARATUS.

1,210,809.

Specification of Letters Patent. Patented Jan. 2, 1917.

Application filed April 8, 1913. Serial No. 759,785.

To all whom it may concern:

Be it known that I, JOHANNES CHRISTIAN JOHANSEN, a subject of the King of Denmark, residing at 27 Welbeck street, Caven-dish Square, London, W., England, have invented certain new and useful Improvements in or Relating to Massage Apparatus, of which the following is a specification.

The present invention relates to massage apparatus of the stationary type in contradistinction to those apparatus which are held in the hand, and although usually the apparatus will be used in a certain position, it is preferably made so that it can be ad-justed, moved or even inclined or turned on one of its sides.

The object of the invention is to provide an apparatus which shall be capable of use under all conditions and for all purposes for which the massage apparatus may be required, and to so construct the machine that while it is provided with a number of tools or applicators, or means for applying a number of tools or applicators in differ-ent positions, the mechanism is provided in a comparatively small compass and is sufficiently protected against damage or interference while it is preferably so mounted or arranged so as to be capable of being ad-justed both vertically (or horizontally) and angularly.

In its general form, the apparatus consists of a casing, which may be in the form of a box, which contains the driving device or motor and various mechanisms for operating the tools or applicators which may be of the tapping and frictional kind, and which may be either permanently arranged in position with their operative surfaces ex-tending out from the box, or may be made so as to be removable therefrom. A plu-rality of holes for the stems of applicators, are arranged on one, or more sides of the box or casing, and preferably one side and the top of the box are provided with both tapping and frictional devices so that one or other can be used according to which-ever is the more suitable for the patient, as regards the position of the applicator and the parts to be operated upon.

I preferably employ an electric motor C in the box B, and supply it with current by means of a flexible conductor C^s, which

passes through a hole in the bottom or side wall of the box, and the various motions for the applicators on the top and sides of the box are all derived from the motor shaft.

Preferably the box or casing B is mounted in an open framework or support a stand-ing a suitable height from the floor say about six feet, in which the box can be ad-justed and held at any desired height from the ground.

I will now describe a convenient embodiment of my invention, reference being had to the accompanying drawings, in which,

Figure 1 shows a front view of the complete apparatus, the uprights forming the frame being shown broken; Fig. 2 is a side view of the upper part of Fig. 1; Fig. 3 being a sectional plan; Fig. 4 is a plan view of the box or casing, partly in section, the lid or cover being removed; Fig. 5 is a vertical section of the box on the line A—A of Fig. 4; Fig. 6 is a sectional side elevation on the line B—B of Fig. 5; Fig. 7 is a detail view of a construction of one of the frictional applicators; Figs. 8 to 13 showing diagrammatically six different positions of the applicator relatively to the main stem; Fig. 14 is a detail view showing how a quick tapping motion can be obtained; Figs. 15 and 16 showing modifications in which double and treble speed motions may be obtained; Fig. 17 is a vertical section of the frame and box wherein the box can be moved angularly as well as vertically; Fig. 18 is a horizontal section of Fig. 17 taken above the box, Figs. 19 and 20 show sec-tional side views on the lines C—C and D—D respectively of Fig. 17.

I will first describe the apparatus in a general way, and then explain construc-tional details.

Referring to Figs. 1, 2 and 3, the frame is formed of four vertical angle irons a forming guides for the box B. These angle irons are suitably mounted on a base a', and connected at the top by a cover a², which may be removable. The inner surfaces of the uprights a are preferably lined with leather or felt a³ or similar material, which will prevent wear of the corners of the box and at the same time act as a silencing and shock absorbing material.

At the top of the frame is arranged a

- winding drum a^4 provided with a handle a^5 , two cords a^6 , a^7 being connected to the drum at one end, their other ends being secured to rods B^4 secured to the sides of the box B .
- 5 The drum a^4 or its shaft, is provided with a toothed wheel a^8 with which a pawl a^9 engages for the purpose of preventing the box sliding down, by reason of its weight, after it has been raised to the desired height by 10 turning the handle a^5 . The standards may be so arranged, or at such distance apart, that it may be possible to introduce the body of a patient between them for treatment with one or other of the applicators.
- 15 The container for the driving and operating mechanism, of the massage tools or applicators is here shown as a rectangular box, entirely closed on all sides with the exception of certain small holes for the stems of applicators as will be described.

In the example illustrated, provision is made on the front of the box B for two rotatory frictional applicators attached to the stems d^7 at the top, two tapping applicators 25 attached to the sockets g^9 at the middle and a rocking member f' carrying two applicators attached to stems f^6 near the bottom. On the top there are two tapping applicators, 30 actuated by lever d^4 , and on one side there are also arranged two tapping applicators actuated by the rod e^0 . Thus there are provided two kinds of frictional tools on the front of the apparatus, as well as tapping tools, while the latter kind of applicators are 35 available both on the top and side of the apparatus.

The interior contents of the box will now be described, referring particularly to Figs. 4, 5 and 6.

40 I secure centrally in the box to the bottom b an electric motor C , mounted on a base plate C' . This motor is supplied with current by means of a flexible conductor which enters the box through a hole in the bottom 45 and is connected to the terminal c^3 .

The motor shaft is provided at the back with a fly-wheel C^2 , and at the front with a crank for operating two rocking levers D , E , from which the top and side tapping motions and the front bottom frictional motion and central tapping motions are respectively derived.

I will first take the upper lever D . This lever is secured to and depends from a horizontal shaft d mounted in suitable bearings d' , d^2 , on the upper part of the motor casing. At its lower end the lever D is slotted at d^3 (Fig. 5) to receive a sliding block in which the crank pin d^* of the motor shaft engages. 55 As the shaft turns the lever D will be rocked about the axis of the shaft d , which, being keyed to the lever D , will also have imparted to it a rocking or slight turning motion about its axis.

60 The shaft d has secured to it, toward its

other end and about centrally above the motor, a cross bar d^4 (Figs. 4 and 5) provided preferably at its ends with rollers d^5 . As the shaft d rocks the two ends of the bar d^4 will, therefore, be moved alternately toward and from the top of the box. Immediately above these rollers are arranged guides d^6 , which extend through the top of the box, for the stems d^7 of tapping applicators. I prefer to construct and arrange these applicators in such manner that their ends d^8 are not acted upon by the rocking bar d^4 until they are forced inward against spring pressure by the pressure exerted upon them by the body or part to be operated upon, as will be explained further on when the front tapping device is described. It will be seen that by this device I obtain an alternate tapping action by the two applicators.

The tapping applicators on the side of the box are also operated from the lever D by means of a link e pivoted to the lever D at a suitable point between d and d^* (Fig. 5). At its other end this link is pivoted to a hanging bar e' pivoted at its upper end to a bracket e^2 or other means of support on the box. At its lower end the bar e' carries a roller e^3 adapted to strike, when the bar is rocked, the end e^4 of the stem e^5 of a tapping applicator. A second bar and applicator are similarly arranged to the side of the bar e' , the two bars being keyed to a common shaft e^6 , so that the two applicators are acted upon simultaneously when the bar e' is rocked by the link e , which, in turn, is reciprocated by the rocking lever D as the motor shaft rotates.

The mechanism for operating the applicators on the front of the box will now be described. At the top (see Fig. 1) are provided means for receiving two rotatory frictional applicators, which are driven by gearing, here shown as arranged at the back of the motor (Figs. 4, 5, and 6). This gearing consists for instance of a train of wheels g , g' , g^2 , g^3 , g^4 , g^5 the wheel g being keyed on the motor shaft and the others suitably mounted on the back of the box, the wheel g^4 gearing with two pinions g^6 , g^7 , fast and horizontal shafts g^7 extending right 110 across the top of the box and projecting through the front wall, as shown in the left hand sectional part of Fig. 4. The two shafts g^7 will thus both be driven at the same slow speed of rotation, although by making the two pinions g^6 of different size, different speeds of rotation may be obtained.

Referring now particularly to Fig. 4, the end of each shaft g^7 passes through a long bearing or journal box B^2 secured to the front wall of the box. These, and other similar bearings, are preferably formed, as shown, in one with a plate B' screwed on to the front of the box and having hub portions B^3 extending through holes formed for 130

that purpose in the wall of the box. Thus, by simply taking out the securing screws the plate B' and with it the parts receiving the various applicators can be removed, when repair or adjustment is desired.

5 Between the shaft g^7 and the inner wall of the bearing B² is a space to receive a tubular stem g^8 provided with a head g^9 to which an applicator can be applied. A recess g^{10} is formed between annular shoulders, in the bearing and on the stem respectively, in which a spiral spring g^{11} is confined, this spring having a tendency to press the stem and head outward.

10 A collar g^{12} is secured, as by a set screw, to the inner end of the stem g^8 . A corresponding collar g^{13} is secured to the shaft g^7 in such position that the opposed faces of the two collars are normally separated by a slight space, and their faces are provided with leather or other suitable surfaces. It will now be seen that as long as no pressure is exerted on the head g^9 the motor may be running and the shaft g^7 rotated without any driving effect being produced on the stem and head, but as soon as pressure is exerted against the applicator secured to the head g^9 the latter is moved inward, against the spring g^{11} , until the two collars or friction disks g^{12} , g^{13} are pressed together, whereupon the motion of the shaft g^7 is imparted to the stem and head and through them to the applicator which thus rotates with them.

15 The action and function of the lever E, which is also rocked by the crank pin of the motor shaft will now be explained. This lever can oscillate about the axis of a shaft f to which it is secured at its lower end, its upper end being slotted and engaged by the crank pin d^* (Fig. 5) which thus acts upon both levers D and E. This shaft f extends out through the front wall of the box (Fig. 4) in order to receive, from the outside, a rocking applicator bar or holder f' . This holder is secured to or provided with a tubular stem f^2 fitting over the shaft f and provided with spring f^3 and friction collar or disk f^4 , adapted to engage a corresponding disk f^5 on the shaft f , in exactly the same manner as the similar parts already described with reference to the rotatory applicator holders driven by the train of gearing $g-g^6$. Thus the motor shaft may be running but the member f' will not rock unless the applicators therein are in use *i. e.*, being pressed against the part to be treated.

20 The bar f' is, as shown in Fig. 1, slotted on either side of its center to receive pins f^6 to which the tubular stems of applicators can be secured. These pins are provided with collars f^7 and lock nuts f^8 as shown in Fig. 4 whereby the pins can be secured in any desired position in the slots. By moving the pins farther away from or

less extended curvilinear motion of the applicators, in a plane parallel to that of the front of the box, can be obtained.

25 There now remains to be described the operation of the tapping applicators on the front of the apparatus. These are derived from the lever E in the following manner:— At a suitable point on the lever lugs h , h are formed having a connecting pin h' . An upright shaft h^2 is journaled in a bearing h^3 attached to the inner front wall of the box, the upper end of this shaft preferably passing through the cover of the box, as shown in Fig. 6, which thus acts as a bearing for its upper end. Secured to the lower part of the shaft h^2 is an arm h^4 having a forked end h^5 which engages on either side of the pin h' . Thus as the lever E is rocked to and fro by the motor shaft, a corresponding rocking motion will be imparted to the shaft h^2 . This shaft has further secured to it a sleeve h^6 having outwardly extending arms h^7 , h^7 provided at their ends with rollers h^8 (Fig. 4). Immediately in the path of these rollers I arrange stems h^9 upon which suitable applicators can be secured, said stems passing through long bearings B², B³, the parts B³ of which fit in corresponding holes formed in the front of the box, as shown in Fig. 4. Each stem has a collar h^{10} fitting the corresponding enlarged portion of the bores in the part B², a spiral spring h^{11} being arranged around the stem h^9 between the collar and the bottom of the enlarged bars. These springs thus keep the stems pressed outward so that even if the motor is running the stems are not acted upon by the rocking arms, unless the applicators are pressed inward as is the case when they are in use.

30 The applicators are here shown as secured to their stems by set screws E', and the outer portion of each stem below the applicator, is screw threaded to receive a milled disk or nut h^{12} . By adjusting the position of the disk upon the stem the extent of the tapping action or stroke can be regulated, as will be readily understood. Either the disk h^{12} or the top of the bearing B², B³ can be provided with a surface of leather, rubber or other sound deadening material h^{13} . It will be clear that as the shaft h^2 rocks the arms h^7 will alternately strike the stems h^9 and drive them outward while the springs h^{11} will return them to their retracted position ready for the next stroke. The upper end of the shaft h^2 when it is made to project through the box may receive an applicator which will thus have a partial rotatory and frictional movement.

35 In Figs. 7 to 13 I show a construction whereby the rotatory applicators, secured to the shafts g^7 , may be arranged so as to have a more or less eccentric rotatory motion. The applicator is mounted so as to rotate but not to move longitudinally upon a stem

40 45 50 55 60 65 70 75 80 85 90 95 100 105 110 115 120 125 130

g¹⁴ the free end of which is forked, the arm *g¹⁵* of the fork being, however, nearer to the stem *g¹⁴* than the arm *g¹⁶*. The head *g⁹* of the tubular stem *g⁸* is provided with a series 5 of holes 1, 2, 3, and 4 into which the arms *g¹⁵*, *g¹⁶* can be inserted. It will be seen from Figs. 8 to 13 that the eccentric motion of the applicator will vary with the way in which the fork is inserted in the head *g⁹* the smallest motion being obtained when the arm *g¹⁶* 10 is inserted in 4 and *g¹⁵* in 2, as shown in Fig. 8, and the greatest when the arm *g¹⁵* is inserted in 4 and *g¹⁶* in 1 as shown in Fig. 13. A spring finger *g¹⁸* may be employed to 15 secure the forked stem to the stem *g⁸*.

It is evident that a similar arrangement could be employed for applicators in other positions on the box whether a rotary or semi-rotary motion is imparted to the stem. 20

In Fig. 14 I show a modification which could be used instead of the side tapping mechanism shown in Fig. 4. Instead of securing a link *e* to the lever *D*, I may extend the stem *e⁵* of the side applicator so that its head *e⁴* will come within the path of the upper end of the rocking lever *E*, a spring being arranged in connection with the stem, as is the case with all the tapping applicators, to normally keep the head *e⁴* out of contact 25 with the lever *E* so that the stem is only operated when pressure is brought to bear upon it from the outside. It will thus be seen that as the lever rocks it will press the stem *e⁵* outward when the lever moves to the right (Fig. 5) the pressure of the patient moving the stem inward as the lever *E* moves to the left. I prefer to provide two such devices—one at each end of the motor, the stem at the back of the motor being 30 suitably operated by an eccentric or cam mounted on the motor shaft between the outer bearing of said shaft and the pinion *g*.

In Fig. 15 I show an oval cam *j* which will give two impulses or strokes to each revolution of the shaft, and in Fig. 16, I 45 show a triangular cam *j¹* which will give three impulses or strokes to each revolution.

It will be observed that in Figs. 4 and 5 I have shown the box as having double walls 50 *b*, *b¹*. While this construction is not essential it is advisable as I can fill the space between the walls with saw-dust, felt, slag-wool or other sound deadening material as it is desirable that the apparatus should 55 work as noiselessly as possible. In Figs. 17 to 20 I have shown a construction in which the box, which is hung from a cable *a⁷* on each side of the frame, is held in a balanced position by a weight *a¹⁰* secured to the other 60 end of the cable, the weight being conveniently arranged to move up and down in a hollow standard *a¹¹* forming one side of the frame, a central vertical slot *a¹²* being formed in the inner wall of the standard 65 for the passage of a lug or angle iron *a¹³* se-

cured on the one hand to the box and on the other hand to the end of the cable *a⁷*. This lug is provided with rollers *a¹⁴* which engage on either side of the slot *a¹²*.

In the construction shown the box is so arranged that it can be turned about its central longitudinal axis, as shown in dotted lines in Fig. 20, and clamped in any desired position. To this end a board *k* is provided on each side of the box, to which boards the brackets *a¹³* are attached. These boards have central circular openings in which trunnions *k¹* secured to the sides of the box fit. Each board *k* is provided with a clamping device for securing the box in any position into which it may be swung on its trunnions. This clamping device may consist, as shown, of a curved block *k²* of wood fiber or other material having a central upwardly extending pin *k³* between the head *k⁴* of which and an inward flange on the tubular guide *k⁵* a spiral spring *k⁶* is arranged so as to normally keep the clamping block out of engagement with the trunnions *k¹*. A lever *k⁷* provided with an eccentric *k⁸* is pivoted upon the head *k⁴* so that when the lever *k⁷* is depressed as shown in Figs. 17 and 20 the head and with it the clamping block *k²* is pressed firmly against the trunnion *k¹* and thus holds the box in 85 adjusted position. On raising the lever *k⁷* the box can be returned to its horizontal position or otherwise re-adjusted. 90

As the box is clear within the two frame members it is obvious that it can be not only tilted but also turned over so as to present any of its four sides to the front of the apparatus. 100

A clamping device may be arranged to act on both trunnions a central lever common to the two being employed for effecting the clamping action. 105

It is obvious that the foregoing is only one example of the way in which an apparatus of this kind can be arranged and constructed, and that numerous modifications may be effected while retaining the broad features of my invention, *i. e.*, box or casing containing a motor and accessory parts operated by the motor shaft the casing containing a plurality of openings for the passage of stems or shafts of applicators adapted to be operated by the motor mechanism to produce different massage movements or to be operated at different speeds. 110 115 120

What I claim and desire to secure by Letters Patent is:—

1. A massage apparatus comprising upright standards, a casing mounted on said standards, means for moving and adjusting the position of the casing, a motor and mechanisms operated by said motor inclosed in said casing and a plurality of openings in the casing for the passage of stems of applicators. 125 130

2. A massage apparatus comprising upright standards, a casing mounted on said standards, means for moving and adjusting the position of the casing, a motor in said casing, a plurality of openings and bearings in said casing for the passage of stems of applicators and members intermediate the motor and the stems for transmitting motion from the motor to the stems to produce 10 massaging movements by the applicators.

3. A massage apparatus comprising upright standards, a casing mounted on said standards, means for moving and adjusting the position of the casing, a motor in 15 said casing, levers adapted to be rocked by said motor and a plurality of openings and bearings in the casing for the passage of stems of applicators adapted to be operated by said levers so as to produce a tapping 20 movement.

4. A massage apparatus comprising upright standards, a casing mounted on said standards, means for moving and adjusting the position of the casing, a motor in said 25 casing, levers operated by said motor, shafts adapted to be rocked by said levers and projecting arms mounted on said rocking shafts, a plurality of openings and bearings in said casing for the passage of stems of applicators adapted to be operated by said 30 projecting arms so as to produce a tapping movement.

5. A massage apparatus comprising upright standards, a casing mounted on said

standards, means for moving and adjusting the position of the casing, a motor and mechanisms operated by said motor inclosed in said casing, a plurality of openings and bearings in the casing for the passage of applicator stems and means whereby the 40 applicators are operated only when outside pressure is applied thereto.

6. A massage apparatus comprising upright standards, a casing mounted on said standards, means for moving and adjusting 45 the position of the casing, a motor in said casing, levers operated by said motor, a plurality of openings and bearings in said casing for the passage of applicator stems, a spring tending to maintain the applicator 50 out of operative connection with said levers, and means for limiting the stroke of the applicator.

7. A massage apparatus comprising upright standards, a casing mounted on said 55 standards, means for moving and adjusting the position of the casing, a motor and mechanisms operated by said motor inclosed in said casing, and a plate secured to said casing and containing a plurality of 60 openings for the passage of applicator stems, substantially as set forth.

In testimony whereof I have affixed my signature in presence of two witnesses.

JOHANNES CHRISTIAN JOHANSEN.

Witnesses:
